United States Patent Office.

GEORGE B. KIRKHAM, OF NEW YORK, N. Y.

Letters Patent No. 60,744, dated January 1, 1867.

KEY-BOARD OF MUSICAL INSTRUMENTS.

The Schedule referred to in these Letters Patent and making part of the same.

TO ALL WHOM IT MAY CONCERN:

Be it known that I, GEORGE BYRON KIRKHAM, of 167 East Thirty-third street, city, county, and State of New York, have invented a new and useful improvement in Organs, Pianos, Melodeons, &c., which I term a "Grand Accord;" and I do hereby declare the following to be a full, clear, and exact description of the same, sufficient to enable one skilled in the art to which the invention appertains to make use of it, reference being had to the accompanying drawings, which form a part of this specification, and in which—

Figure B represents an arrangement in which the whole key-board is shiftable to the right or left.

Figures C and C" represent my special device, and a slightly modified form thereof, for effecting the necessary change of position between the manual keys *z* and the levers *i*.

This improvement, which I term a grand accord, for organs, pianos, melodeons, and other musical instruments with key-boards, is designed to enable the keys to play on the pipes, wires, or reeds a half or full tone, or more, above or below their original or normal position, at the pleasure of the performer. In smaller organs, pianos, &c., where other means are impracticable, the whole key-board, or a portion of it, may be shifted to the right or left, according to circumstances. B represents the entire key-board as movable to the right or left, (the hammers are not shown,) sliding in the groove *b*, and on the rod *c*, moved by the arm *d* and the lever *e*, which projects through the side and rests in little slots, *fff*, which retain it in position when it is moved to the right or left. This arm, *d*, and lever, *e*, with its adjusting screw, *g*, is used in every case, but is not shown in the other drawings, (merely the pin *h* on which *d* fits being represented in the others.) In cases where it is impossible to move the entire key-board, a portion of it, the keys, may be shifted to the right or left, as represented at C C"; the sticks *i* being cut at *j*, and metal or wooden bearings, *kk'*, resting on the sticks *i*, being used; these levers, *k k'*, being held to a common support, *l*, by hinges, or pins and groove. Therefore vocalists and music publishers, to accommodate them, have usually issued the best pieces in different keys for soprano and tenor, or alto and bass. Transposition has always been a long and expensive process, as very few, and only the most eminent, professors are able to transpose a difficult accompaniment at sight. This invention is intended to remedy that defect, and at once places the whole range of music within a vocalist's compass, so that any piece, whether written high or low, can be sung by every person who has the necessary voice and ability. In all key-board instruments, and in pianos especially, great difficulty has been experienced in keeping them up to concert pitch, from flatting, wires breaking, &c. This invention remedies that, as in an instant the instrument can not only be placed at concert pitch, but above it or below it, as desired. Again, in operas or other grand musical performances, when it was wished to raise or lower the pitch to suit the orchestral instruments, or for other reasons, they were obliged to employ a tuner to raise or lower the piano to the tone that was wanted, but this device will at once fulfill those conditions without extra expense. From the great diversity in key-board instruments, the variety of actions, and in organs especially, where the key-sticks play through and between each other in the different banks in an exceedingly complicated and variable manner, together with the pressure of difficulties must be met and overcome in each separate instrument, new or old, as the case may be. I have accordingly selected those movements and connections which are the strongest and most simple, effective, and universal in their adaptation.

Having described my invention, what I claim therein as new, and desire to secure by Letters Patent, is—

1. I claim the levers *k k'* in combination with the manual keys *z z*, &c., and their common support *l*, acting on the levers *i i*, substantially as and for the purpose set forth.

2. I claim the combination of the arm *d*, the lever *e*, with its adjusting screw *g* and slots *ff*, as described and for the purpose set forth.
